United States Patent Office.

BENJAMIN B. SNOW AND THEODORE J. DICKERSON, OF AUBURN, NEW YORK.

Letters Patent No. 80,571, dated August 4, 1868.

IMPROVEMENT IN MACHINE FOR GRINDING THE CUTTERS OF MOWING-MACHINES.

The Schedule referred to in these Letters Patent and making part of the same.

TO ALL WHOM IT MAY CONCERN:

Be it known that we, BENJAMIN B. SNOW and THEODORE J. DICKERSON, of Auburn, in the county of Cayuga and State of New York, have invented certain new and useful Improvements in Machines for Grinding Reaper-Knives; and we do hereby declare that the following is a full, clear, and exact description thereof, reference being had to the accompanying drawings, and to the letters of reference marked thereon, which form a part of this specification, in which—

Figure 1 represents a plan or top view of the machine, and

Figure 2 an end view of the same.

The object of our invention is to provide a device for grinding reaper-knives upon the face of a stone, with as few changes of position as possible; and to this end our improvements consist, first, in a sliding rest working in a slot in the frame for holding the teeth successively in position to be ground; second, in pivoting a clamp to the rest in such manner as to regulate the angle at which the teeth will be ground.

It is desirable that reaper-knives should be ground upon the face of the stone, as the operation can be performed more rapidly on the face than on the side, and the fewer changes of position that are made in bringing the different sections against the stone, the more the grinding will be expedited.

In many cutter-bars, a rib or flange projects upon the under or bevelled side of the sections. This style of cutter-bar cannot be ground upon any side-grinder with which we are acquainted, as the ribs come in contact with the stone before the edge of the section. Again, the necessity frequently arises of grinding out picks or breaks in different parts of the section without grinding away the whole face.

Our machine is designed to meet the requirements stated.

In the accompanying drawings, B represents the stone, which is turned in bearings in the frame A by the handle *b*. A slot, *a*, of greater length than the diameter of the stone, is made in the frame. A rest, C, is movable in this slot, and can be secured in position by the screw and nut *c*. A rod, D, passes through eyes in the rest C, in which it is capable of both longitudinal and rotary motion, and has arms, *d d*, secured to its ends. A clamp, E, is pivoted to the ends of the arms *d d*, in which the reaper-knife, F, to be ground is placed, and held by screws and nuts *e e*.

The operation of the device is as follows:

The rest C is placed at one end of the slot *a*, as shown in fig. 1, so as to present the knife to be ground in proper position to the face of the stone, and the latter caused to revolve. One edge of each section will be brought successively to the stone by moving the rod D longitudinally in the rest C, and to grind the opposite edges of the section, the rest C is moved along the slot *a*, and secured in a corresponding position at the opposite end of the stone.

The rod D being capable of oscillating or rotating partially in the rest C, allows the knife F to be held against the stone at any angle to which it may be desired to grind it, and the swinging motion of the clamp E allows any point of a section, or the whole length thereof, to be brought to the stone.

It will be seen that but one change of position of the rest is required in the operation.

What we claim, and desire to secure by Letters Patent, is—

1. The sliding rest C, moving in a slot in the frame, for the purpose of holding the knife-clamp, substantially as described.
2. The rod D, moving longitudinally in the rest C, for the purpose of successively bringing the sections of the reaper-knife to the stone.
3. The combination of the clamp E and rod D with the rest C, frame A, and fixed stone B, all arranged and operating substantially as described.

In testimony that we claim the foregoing as our own, we affix our signatures in presence of two witnesses.

BENJ. B. SNOW,
THEODORE J. DICKERSON.
